UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 19,817, dated May 6, 1890.

Application filed April 11, 1890. Serial No. 347,542. Term of patent 3½ years.

To all whom it may concern:

Be it known that I, JAMES L. FOLSOM, a citizen of the United States, and a resident of the city of Brooklyn, in the county of Kings and State of New York, have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

15 The accompanying photograph is a face view of a carpet showing my new design.

My design consists of a body A and a border B.

The body A is made up of panel-like divisions or parts bordered by minute gems or dots. Each panel has at its center a group of small conventionalized flower forms, and these are embedded in leaves of irregular shape oc-

cupying the greater part of the outer portion of the panel.

25 The border B has an inner margin of small ornamental figures. The main part of the border is composed of panel-like divisions having groups of flowers and leaves similar in character to those of the body A of the design. 30 The outer part of the border is made up chiefly of line ornamentation.

What I claim as new, and desire to secure by Letters Patent, is—

1. The design for a carpet, consisting of the body A, substantially as shown.
2. The design for a carpet, consisting of the border B, substantially as shown.
3. The design for a carpet, consisting of the body A and the border B, substantially as 40 shown.

JAS. L. FOLSOM.
